UNITED STATES PATENT OFFICE.

JAMES J. DUGGAN, OF CINCINNATI, OHIO.

FURRING CONSTRUCTION.

Application filed February 17, 1928. Serial No. 254,990.

It is the object of my invention to provide new and improved means whereby ceilings and walls may be prepared for receiving plaster, stucco or other plastic coating, or have facings applied thereto; further, to provide novel means whereby my improved attaching means is imbedded in the concrete or other material of which the ceiling or wall is composed; further, to provide novel means whereby attaching tension members, such as wires, have protruding portions which are temporarily arranged in the plane of the ceiling or wall; and, further, to provide an inset arranged to receive the protruding portions of the wires in bent form during construction of the wall or ceiling, the inset being provided with means capable of being arranged in protruding relation to the ceiling or wall to serve as spacing means for the lath or other facing means.

The invention will be further readily understood from the following description and claims, and from the drawings, in which latter:

Fig. 1 represents a perspective view of my improved inset structure in collapsed relation, partly broken away.

Fig. 2 is a perspective view of the same, showing the same attached to part of a form such as used for pouring concrete structures.

Fig. 3 is a cross-section of my improved device showing the inset imbedded in concrete.

Fig. 4 is a cross-section of my improved device with lath attached thereto, taken in the plane of the line 4—4 of Fig. 5.

Fig. 5 is a cross-section of the same, taken in the plane of the line 5—5 of Fig. 4.

Fig. 6 is a cross-section of my improved device, showing one of the spacing parts inclined; and,

Fig. 7 is a bottom view of my improved device showing a different form of stringer, parts being partly broken away.

My improved device is arranged to be used in connection with ceilings, walls and other parts of building structures, and is arranged to be attached to the ceiling or to the inside or the outside of the wall, for receiving plastering, stucco or other material, usually applied in plastic form, although sheet material, for instance, wall board, may also be used in connection therewith, and I shall hereinafter for brevity and

clarity refer to the ceiling, wall or other part to which my improved device is attached, as the foundation.

Illustrating an application of my improved device, 11 represents the mold of a usual concrete ceiling structure, the mold defining the bottom form of the floor 12, which is instanced of concrete, poured into the mold and allowed to harden in usual manner. The mold is exemplified as defining a channel 13 into which the concrete is poured for forming one of the strengthening ribs 14 in the concrete floor or partition 12 which separates stories of a building, the ribs extending downwardly at the ceiling of the room.

These ribs are recurrent in the concrete structure, and it is usual to apply the plastered ceiling below the plane of the lower ends of the ribs. It is also usual to install the piping for heating and other service and electric wiring in the spaces between the ribs, which spaces are usually known as domes. My improved device provides means whereby the domes are free to receive such installation, and protruding parts for attaching lath or other material are avoided on the ceiling during such installation, which is usually done after the concrete is set and the forms are removed but before further manipulation of my improved device.

It has been difficult heretofore to conveniently, properly and economically install lath for plastering or other coating to cover a concrete foundation. To overcome these objections I have provided an inset 15, shown as a pan, the bottom 16 of which is provided with apertures 17. Side walls 18 extend from the bottom and are preferably slanted inwardly or toward each other. The inset is provided with a spacer member normally parallel with the pan and arranged to be extended outwardly from the pan. Thus one of the walls is provided with a flange 19, which is normally bent along the bend 20 substantially parallel with the bottom 16. For a ceiling structure, the pan is in upside down relation in the foundation and for an upright wall structure the pan is in upright relation in the inner face or the outer face of the wall.

A wire 21 is bent to form a lock 22, which is arranged to lock with the concrete, when the concrete has been poured thereabout and set, so as to properly resist the

strains of the ceiling or facing arranged to be held by the wire. This lock is shown in the form of a loop, with the stretches 23, 24, of the wire extending therefrom and passing through the apertures 17. The free ends of the wire are bent in reverse directions or curled, as indicated at 25, and arranged along the inside of the pan between the bottom 16 and the flange 19. The wire forms a tension-member.

The pan is preferably provided with closed corners 26, which avoid the entrance into the pan of fluid and ingredients of the poured concrete. The spacing flange is bent inwardly, preferably so as to be received within the plane of the outer edges 27 of the side walls, so that these edges of the side walls may throughout meet with the form, in order to close the pan, and thereby prevent the entrance into the pan of fluid or ingredients from the poured concrete. The pan is attached to the form, as by means of nails 28, received through holes 29 in the bottom of the pan and nailed into the form.

When the concrete has been poured and set, and the form removed, the spacing flange 19 and the portions 25 of the wires are exposed at the outer face of the foundation, but do not protrude therefrom. The piping and wiring is then preferably installed in the domes. The flange is then bent outwardly, so as to project from the outer face of the foundation, and the wires are also bent, so as to project outwardly for use.

The outer edge of the flange is provided with a notch 31.

A stringer 32, shown as a channel-bar, is received in this notch crosswise of the flange, and the projecting ends of the wires are arranged loopwise about the stringer, and are twisted, as shown at 34, preferably at the side of the stringer, to firmly support the channel-bar with relation to the foundation, and to urge the channel-bar toward the flange 19, which acts as a spacing part for spacing the stringer from the foundation.

My improved insets are arranged at suitable distances apart in the foundation, and the stringers extend across numbers of the insets and are secured thereto. Rows of these insets and stringers are arranged suitable distances apart for properly supporting the lath 35. The lath is supported, preferably by means of wires 36 arranged loopwise around the stringers and through apertures 37 in the lath, the wire being twisted, as shown by the twist 38, for firmly securing the lath to the stringers. The twist 38 is preferably flattened against the lath, and the twist 34 is preferably at the side of the stringer between the foundation and the lath so as not to interfere with the proper plane of the lath. Lath of various char-

acters may be employed, this lath being usually metal lath. Other material or coating such as wall-board, or other material, may also be suitably secured to the stringers.

It is desirable that the lath be in an even plane for convenience and economy in plastering. It often occurs that the face of the foundation in which the insets are located is not in an even plane. If such unevenness occurs, it may be corrected by means of my improved device, by arranging the flange 19 at various angles with relation to said surface. If the flange extends at right angles to the surface, the stringer is supported at greatest distance from said surface. If it is desired to arrange the stringer at less distance from a portion of the surface of the foundation which bulges outwardly, for instance as shown at 39, then the flange 19 is bent to extend at a different angle than at right angles to the surface, for instance as shown in Fig. 6, whereby the unevenness in the foundation is corrected so that the coating is in an even plane. Flanges of different lengths may also be employed.

When the form is removed, the form is pulled away from the inset and the nails 28. The concrete is, however, received under the inwardly bent side walls of the pan, for forming retaining rims 40 around the margins of the pan, for retaining the pan firmly in the foundation, and making it easy to manipulate the flange 19 for bending the same and for bending and manipulating the wires.

The flange 19 is preferably integral with the pan or the wall of the pan from which it extends. The pan is preferably of sheet metal. The pan is preferably dovetailed in the foundation by the retaining rims 40, which aid in holding the pan in place during the bending of the flange 19 to the desired extent, preferably at the bend 20. The sheet metal is preferably sufficiently stiff to properly locate the stringer at the various inclinations of the flange 19.

I have in Fig. 7 shown a different form of stringer, the stringer being there shown as a bar 41, the bar being of suitable length and extending across a number of the insets. The form of stringer and its cross-sectional dimensions or shape are immaterial, such stringers being selected and the distance between stringers and between insets being proportioned according to the weights to be supported or strains to be resisted.

My improved device is especially useful for furring or providing a coating, such as plaster, stucco, or other coating, which is spaced from the foundation. My improved construction is furthermore simple and economical in structure and in use, and it greatly simplifies the attachment of finishing surfaces to foundations.

Having thus fully described my invention, what I claim as new, and desire to secure by Letters Patent, is:

1. In a device of the character described, the combination of a foundation, an inset imbedded therein, said inset provided with a cavity exposed at the outer face of said foundation, and a tension member normally received in bent form in said cavity in the plane of said foundation, said inset provided with a flange normally extending crosswise at the outer exposed end of said cavity and arranged to be bent outwardly for resisting approach of a supported part toward said foundation for spacing said supported part from said foundation, and said tension member arranged for attachment to said supported part for tying said supported part toward said flange.
2. In a device of the character described, the combination of a foundation, an inset imbedded therein, said inset provided with a cavity exposed at the outer face of said foundation, and a tension member normally received in bent form in said cavity in the plane of said foundation, said inset comprising a flange integral with said inset and arranged to be bent thereon, said flange normally extending crosswise of said cavity and arranged to be bent to a plurality of angular positions with relation to the im-

bedded inset for spacing a supported part in selective position with relation to said outer face of said foundation, and said tension member tying said supported part 35 toward said flange.

3. In a device of the character described, the combination of a pan arranged to be imbedded in a foundation, said pan provided with walls and a flange extending 40 from said pan, said flange bendable on said pan for projecting outwardly from said pan and arranged to form a spacing part for spacing a supported part from said foundation, and a tie member extending from said 45 pan to hold said supported part toward said flange.

4. In a device of the character described, the combination of a pan arranged to be imbedded in a foundation, said pan provided 50 with walls and a flange extending from said pan, said flange bendable on said pan for projecting outwardly from said pan, said flange provided with a locating part for laterally locating a stringer, and a bendable 55 tie member normally located in said pan and bendable for tying said stringer toward said flange.

In testimony whereof, I have hereunto signed my name.

JAMES J. DUGGAN.
